UNITED STATES PATENT OFFICE

137,966

DESIGN FOR A WALL PROTECTOR FOR ELECTRIC FLUSH SWITCHES

Mathilda R. Kessler, Chicago, Ill.

Application February 14, 1944, Serial No. 112,573

Term of patent 7 years

(Cl. D26—13)

To all whom it may concern:

Be it known that I, Mathilda R. Kessler, a citizen of the United States, residing at Chicago, in the county of Cook and State of Illinois, have invented a new, original, and ornamental Design for Wall Protectors for Electric Flush Switches, of which the following is a specification, reference being had to the accompanying drawing, forming part thereof.

Fig. 1 is a front elevational view of a wall protector for electric flush switches, showing my new design; and

Fig. 2 is an enlarged section of a portion thereof, taken on the line 2—2 of Fig. 1.

The dominant features of my design reside in the portions shown in full lines.

I claim:

The ornamental design for a wall protector for electric flush switches, as shown and described.

MATHILDA R. KESSLER.
